UNITED STATES PATENT OFFICE.

VINCENZO CAPOLUPO, OF EAST BOSTON, MASSACHUSETTS.

AUTOMATIC FIREARM.

Application filed September 24, 1925. Serial No. 58,443.

This invention relates to certain new and useful improvements in automatic firearms of the type wherein the handle or grip of the pistol constitutes a magazine or chamber 5 for cartridges, the pistol embodying the sliding breech retracted by a recoil movement incident to firing for discharging a spent shell and feeding a new shell into the muzzle of the barrel and forwardly of the tensioned 10 hammer or firing pin.

In the ordinary type of automatic pistol, the spent shell is automatically ejected and a new shell placed in firing position requiring manual operation of the trigger for each 15 firing operation. The primary object of this invention is to provide an attachment for an automatic pistol, preferably of the type embodying a sliding breech in which the pistol is capable of machine gun operation, i. e., 20 repeated firing operation by holding the trigger at its limit of firing movement to retain the trigger connector disengaged from the sear and to construct the breech slide for cooperation with the attachment for automatically 25 operating the sear to release the firing pin.

A further object of the invention is to provide an attachment for an automatic pistol to render the same continuous in its firing 30 operation similar to a machine gun and further to provide means carried by the trigger guard of the pistol and associated with the trigger for limiting movement thereof and controlling operation of said attachment to 35 permit only a single firing of the pistol in the event that the trigger should be inadvertently retained in its firing position.

A still further object of the invention is to provide an automatic pistol of the type 40 above set forth wherein the magazine grip thereof is adapted to be associated with an elongated cartridge chamber constructed in simulation of a cane or walking stick for the purpose of supplying a greater number 45 of cartridges to the pistol.

With the above and other objects in view that will become apparent as the nature of the invention is better understood, the same 50 consists of the novel form, combination and arrangement of parts hereinafter more fully described, shown in the accompanying drawings and claimed.

In the drawings, wherein like reference 55 characters designate corresponding parts throughout the several views,

Figure 1 is a side elevational view, partly

broken away of the magazine cane for the automatic pistol constructed in accordance with the present invention, the head of the cane being retained in position upon the 60 cane stick against spring tension thereon and adapted for automatic projection,

Figure 2 is a side elevational view, partly broken away of the cane with the automatic pistol with the grip magazine thereof mounted 65 upon the upper end of the cane,

Figure 3 is a longitudinal sectional view taken on line III—III of Fig. 1 showing the latch for retaining the cane head in position upon the cane stick and the automatic projection spring,

Figure 4 is a fragmentary side elevational view of the upper end of the cane stick.

Figure 5 is a fragmentary longitudinal sectional view of the upper end of the cane 75 stick with the cartridge magazine chamber thereof shown in full lines,

Figure 6 is a side elevational view of an automatic pistol with the side plates of the hand grip removed to show the attachment 80 in position for cooperation with the trigger connector and sear.

Figure 7 is a side elevational view, similar to Fig. 6 showing the breech slide in its partially retracted position, the trigger in 85 its firing position,

Figure 8 is a fragmentary side elevational view of the pistol showing the attachment for the trigger guard in position to limit 90 firing movement of the trigger and for holding the attachment inoperative relative to the breech slide,

Figure 9 is a perspective view of the attachment for the pistol,

Figure 10 is a detail sectional view taken 95 on line X—X of Fig. 6,

Figure 11 is a perspective view of the lever forming a part of the attachment that operates the sear, and

Figure 12 is a perspective view of the 100 spring arm that carries the block for limiting movement of the trigger.

The present invention relates to an automatic pistol wherein an attachment provided therefor renders the operation of the pistol similar to a machine gun, or in other words, makes the firing of the pistol continuous as long as the trigger is retained in firing position, and also provides for an increased supply of cartridges for use with the pistol, the latter being adapted to be attached to an elongated cartridge chamber,

preferably in the form of a walking stick or cane as shown in Figs. 1 to 5. The reference numeral 1 designates the cartridge chamber in the form of a cane having an upper wall 2 as shown in Fig. 5 through which the cartridge carrier 3 extends, the usual feeding spring for the cartridges being of increased length for supplying the cartridges to the upper end of the tube 3. 5 The cane handle 4 as shown in detail in Fig. 3 contains a coil spring 5 that engages the upper end of the cartridge tube 3 to be compressed thereby when the handle is mounted upon the cane as shown in Fig. 1 and to retain the handle in position against the tension of the spring 5 a tensioned latch lever 6 is carried by the upper end of the cane stick 1 and provided with an operating finger piece 7 projecting through an opening 8 in the cane stick, said latch lever further having a pawl 9 to be projected through the opening 10 in the lower end of the handle 4. It will, therefore, be seen that when the finger piece 7 is operated against spring tension thereon, the pawl 9 will be removed from the opening 10 in the handle and the spring 5 within the latter will eject the handle from the cane stick.

The type of automatic pistol with which the attachment is associated is conventional and generally illustrated in Figs. 6 and 7 wherein the reference numeral 11 designates the body portion or frame of the pistol that includes a barrel 12, a breech slide 13 having a side wall 14, a magazine grip 15 and a trigger guard 16. The hammer or firing pin which is not illustrated is controlled in its operation by the sear 17 that in turn is operated by the connector 18 carried by the trigger 19, operation of the firing mechanism, of course, being controlled by the usual safety grip lever or finger piece 20 at the rear side of the magazine grip 15. In mounting the pistol upon the cane stick 1, 45 the usual cartridge carrier is removed from the magazine grip 15 and the latter is placed upon the upper projecting end of the cartridge carrier or tube 3 as shown in Figs. 2 and 5.

60 The attachment for effecting continuous or repeated firing of the pistol is shown in detail in Figs. 6 to 12 and embodies a plate 21 carrying a depending leg 22 having an opening 23 therein adjacent the lower end that is aligned with an opening in the magazine grip which receives the fastening screw that secures the side plate of the magazine grip in position, the plate 21 and leg 22 being confined within the side plate. It being intended that this attachment is capable of association with various types of automatic pistols, the configuration of the plate 21 and leg 22 may be changed as desired. The screw for holding the plate 21 in position is 65 indicated by the reference numeral 25 in

Figs. 6 and 7. The element embodying the plate 21 and leg 22 is further retained in its proper position by lip projections 26 carried by the upper edge of the plate received in notches 27 formed in the frame 11 of the 70 pistol.

As shown in detail in Fig. 9, a part of the plate 21 is of spaced wall formation and between which walls the lever 28 shown in detail in Fig. 11 is pivotally mounted. The 75 upper end 30 of the lever 28 occupies a position adjacent the lower edge of the side wall 14 of the breech slide 13 while the lower end of the lever 28 terminates in a pin 31 disposed beside the trigger connector 18 and normally disposed adjacent the stop 32 carried by the connector. The upper end 30 of the lever 28 is normally retained in a spaced position from the lower edge of the side 14 of the breech slide through the 80 medium of the loop spring 33 that has one leg 34 thereof anchored to the lower end of the plate leg 22 while the other leg 35 of the spring engages the pin extension 31 upon the lower end of the lever 28 for moving the pin 85 31 in a direction toward the stop 32 as shown in Figs. 6 and 7.

The breech slide 13 is constructed for co-operation with the upper end 30 of the lever 28, the lower edge of the side wall 14 of the breech 13 being cut away as at 36 with a notch 37 formed therein adjacent the rear end of the cutaway portion.

In the operation of the pistol in the usual automatic manner, the breech slide 13 is 100 first manually retracted to position, a cartridge is pushed in the firing chamber and when the breech slide is outwardly projected, the sear 17 engages the hammer or firing pin to hold the same retracted and in 105 a cocked position. The safety lever 20 being normally in the path of firing movement of the sear 17, the safety lever is automatically moved when the magazine grip 15 is grasped for operating the trigger 19, movement of 110 the latter causing the connector 18 to engage the sear 17 to release the firing pin for contact with the cartridge. When the cartridge is fired, the breech slide automatically 115 recoils to permit ejection of the spent cartridge and the supply of a new cartridge into the firing chamber. In order to prevent continuous or machine gun fire of the pistol, an attachment is associated with the trigger guard 19 to limit movement of the trigger, sufficient movement being granted the trigger to cause the connector 18 to operate the sear 17, but to limit movement of the upper end 30 of the lever 28 toward the lower edge 120 of the side wall 14 of the breech slide, it being understood that when the connector 18 is operated, the stop 32 carried thereby engages the pin 31 upon the lever 28 and operates the latter as will be presently described.

The movement limiting means for the 125

trigger includes the provision of a slotted opening 38 in the trigger guard through which the stem portion of a small block 39 projects, the block being disposed within the trigger guard and movable to the positions shown in Figs. 6 and 8. A spring arm 40 pivoted to the projecting end of the stem of block 39 has the hooked free end 41 thereof received in the notch 42 formed in the outer face of the trigger guard 16 for holding the block 39 forwardly positioned out of the path of movement of the lower end of the trigger when continuous firing of the pistol is desired, and when firing of the pistol is to be accomplished by separate operations of the trigger, the arm 40 is moved to the position shown in Fig. 8 and can be retained by a finger of the operator with the block 39 slid rearwardly and disposed in the path of movement of the lower end of the trigger.

When the pistol is to be continuously fired, the trigger 19 is retained in its firing position with the connector 18 disengaged from the sear 17 while the stop 32 upon the connector moves the upper end 30 of the lever 28 into engagement with the side wall of the breech slide to cause the upper end 30 of the lever to be received in the notch 37. When the breech slide moves forwardly, the sear 17 engages the firing pin to hold the same retracted and the end 30 of the lever 28 is received in the notch 37 and the final closing movement of the breech slide operates the lever 28 to move the portion thereof below the pivot point 29 into engagement with the sear 17 to operate the same and release the firing pin. With the trigger 19 retained in its firing position, the upper end 30 of the lever 28 is constantly in the path of movement of the breech slide and continuous firing of the pistol is effected. The upper end 30 of the lever 28 is normally spaced from the breech slide by the spring 33 which permits the usual single firing of the pistol.

It is conventional in this art to provide a means for disengaging the connector from the sear when the trigger is pulled rearwardly and for holding it disengaged as long as the trigger is held in its rearward position, and for this reason specific disclosure of such means herein is believed unnecessary. However, the U. S. patents to W. J. Whiting, Nos. 803,948, November 7, 1905, and 804,694, November 14, 1905, show examples of such means that may be used or form part of the pistol with which the present attachment is employed. While the trigger 19 is shown as of the pivoted type, it is apparent that the attachment may be employed in connection with pistols having other types of triggers. In connection with the function of the lever 20, attention is directed to the U. S. patents to J. M. Brown-

ing, Nos. 747,585, December 22, 1903, and 984,519, February 14, 1911.

While there is herein shown and described the preferred embodiment of the present invention, it is nevertheless to be understood that minor changes may be made therein without departing from the spirit and scope of the invention as claimed.

What is claimed as new is:—

1. In combination with an automatic fire-arm of the breech recoil type, wherein a breech slide retracts a firing pin and places the latter in cocked position to be retained by a sear, and wherein a trigger connector operates the sear, and wherein means is provided for holding the trigger connector disengaged from the sear, means for operating the sear operable by the breech slide. 75

2. In combination with an automatic fire-arm of the breech recoil type, wherein a breech slide retracts a firing pin and places the latter in cocked position to be retained by a sear, and wherein a trigger connector operates the sear, a tensioned lever pivotally supported on the firearm with the upper end thereof disposed adjacent the breech slide, the breech slide being constructed to engage and move the lever for operating the sear to release the firing pin. 85 90

3. In combination with an automatic fire-arm of the breech recoil type, wherein a breech slide retracts a firing pin and places the latter in cocked position to be retained by a sear, and with a trigger connector operating the sear, a tensioned lever pivotally supported on the firearm with the upper end thereof disposed adjacent the breech slide, the breech slide being constructed to engage and move the lever for operating the sear to release the firing pin, and cooperating means 100 105 carried by the lever and trigger connector for limiting movement of the upper end of the lever away from the breech slide.

4. In an automatic pistol, a breech slide, a firing pin, a sear for the firing pin, and a trigger and connector operating the sear, a notch in the breech slide, and a lever adapted to engage the catch on the breech slide for operating the sear when the trigger connector is retained disengaged from the 110 115 sear.

5. In an automatic pistol, a breech slide, a firing pin, a sear for the firing pin, and a trigger and connector operating the sear, a notch in the breech slide, a lever adapted to engage the notch in the breech slide for operating the sear when the trigger connector is retained disengaged from the sear, and cooperating means carried by the lever and trigger connector for moving the lever toward the breech slide when the trigger is operated. 120 125

6. In an automatic pistol, a breech slide, a firing pin, a sear for the firing pin, and a trigger and connector operating the sear, a 130

4

notch in the breech slide, a lever adapted to engage the notch in the breech slide for operating the sear when the trigger connector is retained disengaged from the sear, cooperating means carried by the lever and trigger connector for moving the lever toward the breech slide when the trigger is operated, and means for limiting movement of the trigger to hold the lever spaced from the breech slide.

7. In an automatic pistol, a breech slide, a firing pin, a sear for the firing pin, and a trigger and connector operating the sear, a notch in the breech slide, a lever adapted

to engage the notch in the breech slide for 15 operating the sear when the trigger connector is retained disengaged from the sear, cooperating means carried by the lever and trigger connector for moving the lever toward the breech slide when the trigger is 20 operated, and a block slidably carried by the trigger guard to be moved into and out of the path of movement of the trigger to control operation of the sear by either the trigger connector or lever.

25 In testimony whereof I affix my signature.

VINCENZO CAPOLUPO.
